Primary Examiner—Janice Seeger*(74) Attorney, Agent, or Firm*—Warner Norcross & Judd LLP(57) **CLAIM**

The ornamental design for a work station, as shown and described.

DESCRIPTION

FIG. 1 is a perspective view of the work station;
 FIG. 2 a top plan view thereof;
 FIG. 3 is a bottom plan view thereof;
 FIG. 4 is a rear elevation view thereof;
 FIG. 5 is a front elevation view thereof; and,
 FIG. 6 is a right side elevation view thereof.
 FIG. 7 is a left side elevation view thereof;
 The phantom lines shown are for illustrative purposes and
 form no part of the claimed design;
 The broken lines are for environmental purposes only and
 form no part of the claimed design.
